UNITED STATES PATENT OFFICE.

JOHN W. WURTS, OF ELYRIA, OHIO.

HEATING SYSTEM.

1,267,490.

Specification of Letters Patent. Patented May 28, 1918.

Application filed October 9, 1917. Serial No. 195,567.

To all whom it may concern:

Be it known that I, JOHN W. WURTS, a citizen of the United States, residing at Elyria, in the county of Lorain and State 5 of Ohio, have invented certain new and useful Improvements in Heating Systems; and I do hereby declare the following to be a full, clear, and exact description of the invention, such as will enable others skilled in 10 the art to which it appertains to make and use the same.

My invention relates to heating systems useful, for example in connection with the heating of a set of rooms or apartments, and 15 has for its object improvements in the heating systems now in use, whereby a cold room may be more quickly heated to a suitable temperature, or the air in a room quickly changed for warm, fresh air.

20 The particular objects of my invention and the invention itself will be understood from a description of an embodiment of my invention.

Figure 1 is a general view of a heating 25 system showing an embodiment of my invention.

Fig. 2 shows an alternate means for controlling the air from and to the apartment A.

30 Referring now to the drawing and to the embodiment of the invention shown therein, at A, A' and A'' are shown a set of rooms or apartments, which may be placed in communication through the use of doors B and 35 B'. It will be understood that any number of rooms or apartments may be in the set or may be placed in communication through doors, windows, or otherwise, as desired. At C is shown a furnace which may be of 40 any suitable form. In the embodiment shown the furnace C is provided with a fire box D and with an air cell E. The products of combustion are discharged through a pipe F.

45 A duct is shown at G which will here be spoken of as the first duct, and which communicates at one end 3 with the room A, and at the other end 4 with the air cell E. Better results are secured by connecting the 50 end 4 of the duct G to the air jacket near the bottom thereof. Any suitable form of intake or exhaust for air may be used as shown at 5. A second duct is shown at H, placing the chamber A in communication 55 with E, and which here connects at one end 7 with the duct G and at the other end 8

with the air cell placing the duct G and chamber E in communication. To secure the best results, the duct H is connected to the air cell E at a point above the connection of the duct G thereto. In the embodiment shown, the duct H is connected at 8 near the top of the air jacket.

At J is shown a third duct which is provided for supplying cold air to the furnace. 65 This duct connects at one end 10 with a suitable source of cold air, such as a room or apartment, or the outside of the house, and leads to the air cell E, being preferably connected at a point 11 near the bottom thereof. 70

A fourth duct is shown at L, which is connected at one end with the air jacket and leads to the rooms A' and A''. I prefer to connect the duct L to the jacket at a point 12 above the points 4 and 11. Means are 75 provided for opening either the first or the second duct and closing the other. In Fig. 1 this means comprises two dampers or valves M and N. M is placed in the duct G between 7 and 4 and N is placed in the 80 second duct between 7 and 8.

The operation of the system is as follows: If the room A is cold and it is desired to heat it quickly, the damper M is thrown open and the damper N is closed. The cold 85 air is then drawn from the room A through the duct G to the bottom of the furnace, where it is heated and distributed through the duct L to the remaining rooms in the house. When this operation has been in 90 progress a sufficient time, and generally a short time is sufficient, as I have found by experiment, the damper M is closed and the damper N is opened, whereupon hot air is 95 immediately supplied to the room A through the duct H and the portion G₁ of the duct G. Under normal conditions cold air is drawn in through the duct J, heated and supplied to the various rooms of the set through the ducts H, L and the portion G₁ 100 of the duct G. Of course said air may be drawn into E through J and G simultaneously.

In Fig. 2 I have shown a single damper or valve at O, which is hinged at o and 105 which may be positioned at o-o' across the entrance to the duct H' or at o-o'' across the entrance to the portion G₂ of the duct G'. I prefer to connect a chain p to the damper O to control the same. A hook q 110 is provided on the wall or some other stationary object to coöperate with the hook r

to hold the damper O in the position $o-o'$. The damper may be weighted, as shown at s so that it will normally take the position $o-o''$ when the chain is released.

5 Of course, when the damper is in the position $o-o'$ cold air will be drawn from the room A, and when the damper O is in the position $o-o''$ hot air will be furnished thereto. I have found by actual experiment 10 that by the use of my invention I can very quickly heat a cold room. The advantage of this system, in general, will be appreciated, and in addition, there is a special advantage where it is desired to keep a room 15 cold and then suddenly heat it, such for example, as the bed rooms of those who sleep with the windows open and who desire to heat them quickly in the morning.

It will be seen that I may quickly withdraw 20 the foul air from a room by opening the portion G_2 of the duct G and closing the duct H. This is especially advantageous where it is desired to empty a bed chamber at bed time and replenish it with fresh air, 25 though, of course, the air in any room may be quickly exchanged for warm, fresh air at any time.

The device 5 may be placed at any convenient place in the room, either the floor, 30 the ceiling or the side walls. The furnace may be placed at any suitable location, preferably in the cellar of the building whose heating it controls. The chain p may lead

to any convenient place, such, for example, as to the room A.

I have shown this embodiment and these details for the purpose of describing my invention. It will be apparent that departures may be made both from the form and details without departing from the 40 spirit of the invention.

I claim:—

In a heating system, the combination of a furnace for heating air provided with an air jacket thereabout, a first duct communicating with one of a set of rooms or apartments at one end and connected at the other end near the bottom of the air jacket into which it opens, a second duct opening at one end into the air jacket near the top 50 thereof and at the other end into the first duct, means to close either duct and open the other, a third duct placing said air jacket in communication with a source of cold air connected to the air jacket near 55 the bottom thereof and a fourth duct connected to the air jacket near the top thereof and placing said air jacket in communication with all the other rooms or apartments of said set than the room with which the 60 first duct communicates.

In witness whereof, I have hereunto signed my name this 28th day of September, 1917.

JOHN W. WURTS.
